UNITED STATES PATENT OFFICE.

JOHN H. JEPSON, OF MINNEAPOLIS, MINNESOTA.

KNEE-JOINT FOR ARTIFICIAL LIMBS.

No. 927,973.

Specification of Letters Patent.

Patented July 13, 1909.

Application filed November 23, 1907. Serial No. 403,463.

To all whom it may concern:

Be it known that I, JOHN H. JEPSON, a citizen of the United States, residing at Minneapolis, in the county of Hennepin and State of Minnesota, have invented certain new and useful Improvements in Knee-Joints for Artificial Limbs; and I do hereby declare the following to be a full, clear, and exact description of the invention, such as will enable others skilled in the art to which it appertains to make and use the same.

My invention relates to artificial legs and has for its object to provide an improved knee joint or pivotal connection between the metallic straps used to connect the lower leg section to the upper leg section.

To the above ends the invention consists of the novel devices and combinations of devices hereinafter described and defined in the claim.

The invention is illustrated in the accompanying drawings wherein like characters indicate like parts throughout the several views.

Referring to the drawings, Figures 1 and 2 are views in side elevation, showing a pair of metal straps of the kind above indicated connected by my improved joint, looking at the outer side thereof. Fig. 3 is a fragmentary view in side elevation, showing the pivotally connected end portions of the two metal straps, looking at the inner side thereof. Fig. 4 is a view corresponding to Fig. 3, but with some parts broken away and some parts sectioned. Fig. 5 is a front edge elevation of the parts shown in Figs. 3 and 4; and Fig. 6 is an enlarged section taken on the line $x^3 x^6$ of Fig. 4.

The numerals 1 and 2 indicate, respectively, the upper and lower metal straps, one of which and, as shown, the latter of which, is bifurcated at its pivoted end to form laterally spaced ears 3 that embrace and closely engage the sides of the lower end of the upper strap 1. The lower end of the upper strap 1, which works between the ears 3, is bored through to form a seat that closely fits a hub or so-called "bolt" 4. This hub 4, at one end, is provided with a slight enlargement that forms an annular shoulder 5. The inner end of thus hub 4 bears against the inner surface of one of the ears 3, and the enlarged outer end thereof closely fits a seat formed in the other ear. A screw 6, the head of which is preferably slightly countersunk into the ear 3 against which the reduced end

of the hub 4 bears, has screw-threaded engagement with said hub and rigidly clamps the same in working position in respect to the two ears 3. The shoulder 5 of the hub 4 prevents spreading of the said ears. That portion of the lower end of the strap 1 that works between the ears 3 is formed with a segmental bearing surface 7 that extends concentric to the axis of the joint, to-wit, to the axis of the hub 4, and terminates in tangentially extended stop surfaces 7^a and 7^b. The bifurcated end of the strap 2 between the ears 3 is formed with a straight stop surface 8 that extends tangentially to the segmental bearing surface 7 and closely engages the said surface 7 when the straps are moved pivotally, one with respect to the other. Also with this construction it follows that when the straps 1 and 2 are moved into approximately straight line with each other, as indicated in Figs. 1 and 4, the tangential stop surface 7^a of the strap 1 will strike flatwise and throughout its length against the bearing surface 8; and likewise, when the two straps are moved to their other extreme position, as indicated in Fig. 2, the tangential stop surface 7^b will be thrown flatwise against the said bearing surface 8. It also follows that at all times, whether in extreme positions, or in an intermediate position, the joint has a double bearing which greatly reduces the wear between the frictionally engaging parts of the pivotal joint. For instance, when the straps are in intermediate positions, the joint has a bearing between the hub 4 and its seat in said strap 1, and between the segmental bearing surface 7 of said strap 1 and the tangential bearing surface 8 of the strap 2. This, as is evident, gives a joint that will not only wear a long time, but which will be free from all slack or lost motion incident to wear.

These knee joints in artificial legs are subject to considerable strains and to constant wear, and the coöperating stop surfaces for limiting the movements of the joint are subject to a sort of pounding action that tends to distort the same. This is minimized in the present joint by the tangentially engaging stop surfaces of the two straps.

Preferably the lower end of the strap 1 is provided in one face with an annular oil groove 9 which has an upwardly extended entrance groove 10 through which latter the oil may be introduced into the said oil

groove 9 and from thence to the frictionally engaging parts of the joint.

It will, of course, be understood that in practice two pairs of pivotally connected straps 1 and 2 will be used to connect the lower leg section to the upper leg section of the artificial leg and that these will be applied one pair to each side of the leg. Preferably the straps 1 will be secured to the 10 upper leg section, while the straps 2 will be secured to the lower leg section. For convenience, these should be applied to the leg with the heads of the screws 6 outward. In actual practice the improved joint above described has been found highly efficient for the purposes had in view.

From what has been said it will be understood that the improved joint above described is especially adapted for use in connection with artificial legs designed for amputations below the knee. It is, however, capable of more general use.

The bearing surface of the hub 4 and the engaging seat in the strap 1 have true 25 cylindrical surfaces, that is, are not tapered or conical. A tapered or conical surface wears unevenly and the larger diameter

thereof wears away more rapidly than the smaller diameter, thus soon giving play between the parts, while true cylindrical surfaces have an even bearing throughout, and consequently reduce the wear to a minimum. 30

What I claim is:

In a device for connecting the sections of an artificial limb, the combination with a 35 metal strap having laterally spaced ears 3 and a tangential bearing surface 8 between said ears, of a metal strap 1, one end of which is located between said ears and is formed with the segmental bearing surfaces 7 40 and tangential stop surfaces 7^a—7^b engageable with said bearing surface 8, a hub 4 fitting a seat in said strap 1 that is concentric to said segmental surface 7, said hub having a shouldered end 5 seated in one of 45 the ears 3, and a screw securely clamping said hub to the other ear 3, substantially as described.

In testimony whereof I affix my signature in presence of two witnesses.

JOHN H. JEPSON.
